DESIGN FOR EMBROIDERED LACE

Willy H. Erpf, Fairview, N. J., assignor to Tobler & Hoenig, New York, N. Y., a partnership of New York

Application December 29, 1934, Serial No. 54,636

Term of patent 3½ years

To all whom it may concern:

Be it known that I, Willy H. Erpf, a citizen of the United States, residing at 302 Day Avenue, in the county of Bergen, city of Fairview, and State of New Jersey, have invented a new, original, and ornamental Design for Embroidered Lace, of which the following is a specification, reference being had to the accompanying drawing, forming part thereof.

The drawing shows a face view of a piece of embroidered lace embodying my design.

I claim:

The ornamental design for embroidered lace, substantially as shown.

WILLY H. ERPF.
